ELECTRIC HEAT REGULATING SWITCH

Richard Collier, Esher, England

Application May 14, 1954, Serial No. 429,933

Claims priority, application Great Britain
October 19, 1953

5 Claims. (Cl. 200—122)

This invention relates to an electric heat regulating switch of the type adapted to operate cyclically under the control of a thermal element which regulates the overall heating effect of the current supply by controlling the relative durations of the periods in each cycle during which the switch is closed and open respectively. This type of switch is particularly useful for controlling the hotplates of electric cookers and enables the heating effect of such hotplates to be regulated so that they can be used efficiently for simmering.

The present invention provides an improved switch of this type which is simple, reliable, inexpensive to manufacture and easily adjustable over a wide range, so that the period during which the current is switched on in each cycle can be varied from almost the whole duration of the cycle to only a small fraction thereof.

More specifically the object of this invention is the provision of a switch of the type referred to comprising a pivotal bimetallic strip and switch plate in which the pivotal connection is of simpler construction than hitherto and in which the strip and plate are readily assembled.

Another object of the invention is to enable said strip and plate to be removed and replaced in a simple manner.

Yet a further object is to provide a spring connection between the bimetallic strip and the switch plate whereby the plate has a snap over action and to utilise said spring to maintain pivotal connection between said strip and plate and bearing or support members therefor.

Another object is to provide that removal of the strip and plate may be effected on removal of the spring, said strip and plate being unattached to the bearing or support members.

The invention and its subsidiary features will be fully understood from the following more detailed description by way of example of one embodiment thereof, reference being made to the accompanying drawings in which:

Figure 1 is a sectional side view of a complete switch;

Figure 2 is a top plan view of the body of the switch with cover plate, control knob and cam plate removed;

Figure 3 is an inverted plan view of the cover plate and cam plate with the relative position of a contact spring shown in broken lines;

Figure 4 is an inverted plan of the body of the switch;

Figure 5 is a fragmentary detail view;

Figure 6 is a fragmentary sectional view taken on the line 6—6 of Figure 1, and

Figure 7 is a diagram showing a development of an operative surface of the cam plate seen in Figure 3.

As shown in the drawing, the main moving contact 1 of the switch (Figure 1) is carried by a bifurcated switch plate 2 (Figures 1 and 2), the two legs of which are fulcrumed at their ends on two aligned bearing members or hooks 3 carried by a plate 4 fixed to a casing 5 that forms the switch base. The members 3 are bent to form V-grooved bearing members or hooks which project through slots 300 provided for them in the two legs of the switch plate as shown in Figure 5.

Mounted on the plate 4 between the bearing members

2

3 is a bimetallic strip 6 formed at one end with a tongue 7 which is thrust through a slot in the plate 4 (see Figure 6) and attached to an adjusting lever 9 by which the bimetallic strip 6 can be rocked up and down for a purpose which will appear hereinafter. The strip 6 has shoulders 8 adjacent the root of the tongue 7 that bear against the face of the plate 4, which thus constitutes a pivotal bearing support for the strip 6. The bimetallic strip 6 extends between and approximately parallel to the legs of the bifurcated switch plate 2 and has a rockable free end 6a spaced a short distance from the crutch 10 which constitutes a movable free end of the switch plate. In the gap thus formed is lodged a C-spring 11 bent at its ends to form V-grooved pivot bearings one of which rests against a knife-edge formed by the free end 6a of the bimetallic strip 6 whilst the other rests against a parallel knife-edge formed by the crutch 10 of the switch plate 2. The construction is such that the C-spring 11 constantly applies longitudinal forces of compression and tension to the switch plate 2 and bimetallic strip 6 respectively and thereby holds these members firmly in engagement with the pivot bearing members 3 and 4 that support them.

The rocking movement of the switch plate is limited in one direction by the engagement of the moving contact 1 with a cooperating fixed contact 12 and in the opposite direction by a stop 13 (Figure 1). The bimetallic strip 6 has a greater range of movement so that it can be moved to either side of the switch plate in either position of the latter, the relative movement of the two free ends 10 and 6a serving to compress the spring 11 through a dead centre position where it is compressed to a major degree. The position of the bimetallic strip is controlled by a rotatable cam plate 14 operated by a knob or hand-wheel 15 and engaging a cam-follower 16 mounted on the lever 9, the knob 15 and cam plate 14 being carried by a cover plate 30 attached to the casing 5. A coiled compression spring 17 acting on the end of the lever 9 attached to the tongue 7 constantly tends to rock the bimetallic strip 6 and adjusting lever 9 in the clockwise direction as seen in Figure 1 so as to hold the cam-follower 16 up to the cam 14.

An electric heating coil 18 wound on a strip of mica or other suitable material attached to the bimetallic strip 6 is provided for heating the bimetallic strip when current is switched on by the closing of the contacts 1 and 12, the strip being arranged so that it curls upwards (Figure 1) when heated. The mechanism is adjusted so that, when the bimetallic strip is cold, it assumes a position on the side of the switch plate remote from the fixed contact; and consequently the pressure of the C-spring normally tends to hold the switch contacts closed in the manner shown in Figure 1. The flow of heating current causes the bimetal to curl upwards so that it ultimately reaches a position above the switch plate 2. During this movement, as soon as the C-spring 11 has passed through the dead-centre position, it expands suddenly and causes the switch plate 2 to move over to the open-contact position with a snap-action. The bimetallic strip 6 then cools and moves the C-spring 11 back to its original position so as to re-close the switch contacts, the switch plate 2 again moving with a snap action as soon as the C-spring 11 passes the dead centre. The switch continues to cycle in this way so long as the current supply is maintained.

The ratio between the intervals during which the switch is open and closed respectively during each cycle depends upon the setting of the bimetallic strip 6 and can be altered by adjusting the cam plate 14. The switch controls the average rate of heat supply to a hot-plate by controlling this ratio in a way which is so well known in the art that it need not be described herein.

The construction according to the invention is simple,

inexpensive and reliable. It can readily be designed to have a wide working range of adjustment and may be arranged so that, after being set upwards (i. e. in the direct to increase the heat supply to a hot-plate) the switch will remain closed for a sufficient length of time to allow the hot-plate to be heated quickly to a temperature at or near that at which it is to be maintained.

As shown in Figure 3 of the drawing, the cam plate 14 is formed at its lowest point with a depression 19 into which the cam-follower 16 falls when the knob 15 is adjusted to an "off" position, this providing a position in which the device is definitely switched off. To guard against any risk of undesired closing of the supply circuit should the bimetallic strip be cooled excessively when the switch is in this position, an auxiliary contact spring 20 carrying a contact 21 cooperating with a fixed contact 22 is arranged to be controlled by the cam plate 14. This contact spring has a projection 23 which is arranged to bear against the cylindrical edge of the cam plate 14, and a recess 24 is provided in the edge of the cam plate in such a position that the projection 23 enters the recess and allows the contact 21 to spring away from the contact 22 when the control knob 15 is turned to the "off" position above referred to. When the knob is moved away from this "off" position, the projection 23 rides out of the recess 24 and rests on the cylindrical surface of the cam plate 14, the contact 21 being thus pressed into engagement with the contact 22 in all positions of the control knob except the "off" position. The contacts 21 and 22 are so connected in the circuit to be controlled in series with the contacts 1 and 12 that the current supply to the heater under control cannot be switched on when the controls 21 and 22 are separated.

The cam plate 14 is surficially cammed to move the lever 9 through a convenient range of adjustment as the knob 15 is rotated. This cam surface is shaped as shown in Figure 7 so that it has a working area 25 extending from a low point 26 at one end of its range of adjustment to a high point 27 at the other end of its range of adjustment, the low point coinciding with the depression 19. As can be seen in Figure 7, the cam surface is shaped at 28 so that there is a fair lead over which the follower 16 can ride in either direction. The cam thus has an endless surface over which the follower 16 can ride in either direction so that the knob can be turned from "off" to the full on position or from full on to "off" without having to be rotated through its whole range of adjustment.

The part shown at 29 is a stop pin provided for so limiting the swinging movement of the bimetallic strip 6 as to prevent it from falling out when the cover plate 30 is removed from the casing 5.

The device is provided with four contact terminals 31 on the bottom of the casing 5 for connecting the contacts 1, 12, 21 and 22 and the heating coil 18 in the supply circuit of a heater to be controlled.

I claim:

1. A heat-regulating electric switch including in combination a casing, a bearing member secured to the casing, a switch plate engaging the bearing member and attached thereto by a tongue-and-slot connection, said plate having a movable free end, a pair of co-acting contacts within the casing one of which is movable and carried by the free end of the switch plate, a support member secured to the casing, a bimetallic strip within the casing engaging the support member and attached thereto by a

tongue-and-slot connection and having a rockable free end adjacent the free end of the switch plate, an electric heating coil disposed in a position to heat the bimetallic strip and a compression spring connecting together the respective free ends of the switch plate and bimetallic strip and holding the switch plate and bimetallic strip firmly in pivotal engagement respectively with said bearing member and support member, said switch plate being operable by the bimetallic strip through the medium of said spring, relative movement between the free ends of the switch plate and bimetallic strip compressing the spring through a dead-center position, the said spring holding the switch plate firmly in the contacts closed position at normal room temperature.

15 2. A heat-regulating electric switch including in combination a casing, a bearing member secured to the casing, a switch plate engaging the bearing member and attached thereto by a tongue-and-slot connection, said plate having a movable free end, a pair of co-acting contacts within the casing one of which is movable and carried by the free end of the switch plate, a support member secured to the casing, a bimetallic strip within the casing engaging the support member and attached thereto by a tongue-and-slot connection and having a rockable free end adjacent the free end of the switch plate, an electric heating coil disposed in a position to heat the bimetallic strip, and a C-shaped plate spring compressed between the free ends of the switch plate and bimetallic strip and urging the switch plate and bimetallic strip firmly into pivotal engagement respectively with said bearing member and support member, said switch plate being operable by the bimetallic strip through the medium of said spring, relative movement between the free ends of the switch plate and bimetallic strip compressing the spring through a dead-centre position, the said spring holding the switch plate firmly in the contacts closed position at normal room temperature.

20 3. A heat-regulating electric switch as claimed in claim 2 wherein the switch plate has a slot and the bearing member comprises a leg having a V-groove, the leg entering said slot, the switch plate being held in pivotal engagement with said groove by said C-spring.

25 4. A heat-regulating electric switch as claimed in claim 2 wherein the bimetallic strip has a tongue and the support member has a slot to receive the tongue, the tongue being held in pivotal engagement with the slotted support member by said C-spring.

30 5. A heat-regulating electric switch as claimed in claim 2 wherein the C-spring applies longitudinal forces of tension and compression to the switch plate and bimetallic strip respectively and thereby holds these parts firmly in pivotal engagement with the bearing and support members respectively.
